Primary Examiner — T Chase Nelson*Assistant Examiner* — Ania Aman(74) *Attorney, Agent, or Firm* — Tianhua Gu; Global IP Services(57) **CLAIM**

The ornamental design for a generator motor, as shown as described.

DESCRIPTION

FIG. 1 is a frontal view of the generator motor showing my new design;

FIG. 2 is a rear view of thereof;

FIG. 3 is a left side view of thereof;

FIG. 4 is a right side view of thereof;

FIG. 5 is a top plan view of thereof;

FIG. 6 is a bottom plan view of thereof; and,

FIG. 7 is a perspective view thereof.

In the drawings, the broken lines depict unclaimed features of the generator motor that form no part of the claimed design.
